UNITED STATES PATENT OFFICE.

JOSEPH W. HOLMAN, OF CLEVELAND, OHIO.

MOLD FOR SIDEWALK CONSTRUCTION.

1,080,693.

Specification of Letters Patent.

Patented Dec. 9, 1913.

Application filed February 3, 1912. Serial No. 675,337.

To all whom it may concern:

Be it known that I, JOSEPH W. HOLMAN, a citizen of the United States, and a resident of Cleveland, county of Cuyahoga, and 5 State of Ohio, have invented a new and useful Improvement in Molds for Sidewalk Construction, of which the following is a specification, the principle of the invention being herein explained and the best mode in 10 which I have contemplated applying that principle so as to distinguish it from other inventions.

My invention relates to a simple mold construction for use in forming sidewalks, in 15 which are set lights of glass, such as are used over cellars extending into the street.

Various types of construction have been used for the purpose of forming the concrete molds around the lights of glass, but 20 serious difficulties have been met with in the use of each type. It is possible to form a very firm and lasting sidewalk by the use of metal molds which, however, must be left in the sidewalk after completion, thus necessitating a considerable expense for materials 25 at every sidewalk laying. Another type of mold in considerable use allows the withdrawal of the molds after the laying of the sidewalk, but necessitates the placing of the 30 reinforcing rods in such a position relative to the lights of glass that leakage is almost sure to result.

With the present construction it is possible to form a very secure sidewalk and to 35 place all of the reinforcing members or tie rods below the level of the lights of glass, which is a very advantageous construction for this purpose.

To the accomplishment of these and related ends, said invention, then, consists of the means hereinafter fully described and particularly pointed out in the claims.

The annexed drawing and the following description set forth in detail certain mechanism embodying my invention, such disclosed means constituting, however, but one of the various mechanical forms in which the principle of the invention may be used.

In said annexed drawing:—Figure 1 is a 50 view in perspective of a sidewalk which has been formed with my molds and which is shown attached to the wall of the building and the side wall of the cellar; Fig. 2 is a section, taken through a sidewalk of this 55 type, parallel to the wall of the building;

Fig. 3 is a side view of one of the molds; Fig. 4 is a side view of the mold showing the supporting member attached thereto; Fig. 5 is a front elevation of the supporting member, and Fig. 6 is an end elevation of 60 the same; Fig. 7 is a view in perspective of two of my mold members when in operating position; Fig. 8 is a section taken at right-angles to the line of section of Fig. 2, showing a mold in position and also the supporting member and the external supporting means.

From Fig. 1 the general construction of a sidewalk formed by means of my molds will be readily apparent. A heavy reinforced concrete rib 1 is shown attached to the front of the building, and from this run the deep ribs 2 at right angles to the same. Another reinforced rib 3 will be used at the side of the sidewalk adjacent to the side of 70 the cellar. It will be noticed that the alternate ribs 2 are heavy and the intermediate ribs 4 are of light construction. Transversely disposed ribs 5 are shown, and between these transversely disposed ribs and 75 the longitudinal ribs 2 and 4 are placed the lights of glass 6.

In Fig. 2 the general construction of my molds is shown. A series of pairs of molds will be used, each pair comprising two complementary molds 7 and 8, which are provided with laterally extending flanges 9 on the adjacent faces of the same, and with other laterally extending flanges 10 on the opposite sides of the same. The first named 85 flanges are near the top of the mold member, and the flanges 10 will be at or near the bottom of the same. The molds are laid down adjacent and parallel to each other with the flanges 9 in contact, as shown 90 in Fig. 2, when they will be engaged by a supporting member 11 which has an inwardly projecting lug 12 adapted to engage the under side of the flanges 9, and a base flange 13, upon which are mounted 95 suitably formed lugs 14, which will engage the recesses 15 in the bottom of the mold members. In this way, the two complementary mold members will be supported at either end by a single supporting member, which will itself be supported from any suitable external means. The external means which will be provided may consist of two members 20, which will be held upon supports 21 at either end, resting upon the 100 110

ground. It will be understood that these supports just referred to, are merely a scaffold which will be temporary and will be no part of the building after completed. By 5 reason of the disposition of the flanges 9 and 10 upon the mold members, it will be seen that alternately deep and shallow ribs will be formed. After the concrete has been 10 poured in around the mold a suitable drawing member (not shown) having a projecting lug on it will be attached from the under side to a lug 16 on the front of the supporting member, the two lugs engaging, as will be readily understood. A downward pull 15 on the same will then withdraw the supporting member from its engagement with the mold member. The latter can be similarly withdrawn from engagement with the concrete itself by using the same member 20 which will be attached to the apertures 17 in the mold members. It will be obviously a matter of indifference as to whether the supporting member projects below the mold member when in engagement, as shown in 25 Fig. 4, or not, as the latter can be suitably supported by a very slight change in the form of the lug 14, without the necessity for the supporting member hanging below the same. The drawing member is not in itself an essential 30 part of my invention, and any suitable means for this purpose may be provided. In actual practice the mold members may be of any suitable length, but will most readily adapt themselves to this use if 35 made of a length sufficient to enable them to extend from side to side of the space to be covered. They may, however, comprise a member such as is shown in Fig. 3, in which case the mold will have space for but three 40 lights of glass instead of any desired number, as is possible when the molds are designed to extend fully across the space to be covered.

From the foregoing description the general 45 construction of the molds will be evident. Each mold is substantially rectangular in plan, having a flange on each of its long sides. It also has transverse troughs or grooves 18 at equal intervals, thus forming 50 the mold into square areas. Within these areas the mold is cut away, permitting the engagement of a light of glass 6 therein. Each light of glass is provided with flanges 55 19 for a purpose which will be hereinafter described.

After the mold members have been attached to the supporting members and are parallel and in contact with each other, reinforcing members 20 will be placed in the 60 various troughs formed between the molds and across the same, and the lights of glass, which will preferably be of the form shown in dotted lines in Fig. 2, will be inserted in the apertures which are provided by cutting 65 away the upper side of the molds. The

flanges 19 on the glass rest on the sides of the aperture in the mold and extend over the same. The concrete may therefore contact the flanges from above and below, completely locking the lights of glass in the 70 sidewalk. It will be seen in Fig. 2 that each of the reinforcing members is below the bottom of each light of glass, while the main reinforcing members will be a considerable distance below the same.

In Fig. 7 I show a view in perspective, of 75 two of my mold members which are together in the position shown in Fig. 2. It will be seen that each of these members has ribs running longitudinally of the same, and other transversely disposed ribs, thus cutting the mold up into a number of squares, 80 in which, or upon which, the glass will be inserted. As here shown, the molds are cut away in these sections for the sake of lightness and cheapness, but it will be understood that this is not necessary except where the lights of glass have projecting flanges and part of the body depending below these flanges.

Fig. 8 shows a longitudinal section of a sidewalk, and the molds forming the same, and shows also the supporting members in position. When it is time to draw the mold, the supports 20 and 21 will be removed, 90 when the members 11, and the mold members will be retained in their positions only by the adherence of the concrete. The next step will be to remove the members 11, by the means already described, which will 95 leave a triangular space between each end of the mold members and the adjacent concrete wall. It is impossible, or practically so, to draw a mold evenly, and it is therefore necessary to draw downwardly on one 100 end, letting the other end pivot, as is shown in dotted lines in Fig. 8. It will be noticed that my construction adapts itself readily to this method of procedure, as by reason of 105 the triangular space between the mold and the concrete, it is possible for the lower right-hand end of the mold to swing to the right, pivoting about the upper right-hand corner of the mold. In this way the concrete ribs which have been formed by the 110 troughs in the mold, are not injured by the drawing of the mold, as the latter swings freely away from these ribs.

Simplicity of construction and convenience of operation are two of the more important advantages secured by the use of my improved molds. Other advantages are the strength of the sidewalk made by the molds and the comparatively low cost of the same, since the molds can be used over and over 115 again.

Other modes of applying the principle of my invention may be employed instead of the one explained, change being made as regards the mechanism herein disclosed, pro- 120 125 130

vided the means stated by any of the following claims or the equivalent of such stated means be employed.

I therefore particularly point out and distinctly claim as my invention:—

1. In mold construction, the combination of two complementary molds disposed adjacent and parallel to each other, each of said molds having a laterally projecting flange 10 on the side adjacent said other mold, said flanges being adapted to contact throughout the length of the molds, thereby forming a trough, and a supporting member disposed at either end of said molds and adapted to 15 removably engage, and support said molds.

2. In mold construction, the combination of a plurality of complementary molds, disposed adjacent and parallel to each other, each pair of said molds having laterally projecting complementary flanges a short distance below the top on the adjacent faces of the same, and other laterally projecting flanges on the exterior faces of the same, said other flanges being a greater distance 25 from the top than said first-named flanges and being adapted to contact similarly formed and disposed flanges on the exterior faces of the adjacent molds, and a supporting member adapted to removably engage 30 the ends of each pair of complementary molds, thereby supporting the same.

3. In a mold construction, the combination of two complementary molds disposed adjacent and parallel to one another, each of 35 said molds having a plurality of transversely disposed troughs adapted to register with the troughs of said other mold, laterally projecting flanges on the adjacent faces of said molds, said flanges being adapted to contact 40 throughout the length of said molds, thereby forming a second trough, and a supporting member adapted to removably engage the ends of each pair of complementary molds, thereby supporting the same.

4. In a mold construction for forming side 45 walks, the combination of a series of molds disposed adjacent to each other, each of said molds having a plurality of transversely disposed troughs adapted to register with the troughs of the other molds, and laterally 50 projecting flanges on the adjacent faces of said molds adapted to contact throughout the length of said molds, thereby forming other troughs, each of said molds having apertures between said transverse troughs 55 adapted to receive a light of glass, said glass extending slightly over the edges of said mold into said troughs.

5. A mold member for sidewalk construction, comprising a rectangular mold member having a laterally projecting flange on either side thereof, such flanges being at unequal heights on such sides, said mold member having transversely disposed troughs 60 at equal intervals throughout its length. 65

6. A mold member for sidewalk construction, comprising a rectangular mold having a laterally projecting flange on either side thereof, such flanges being at unequal heights on such sides, said mold having transversely 70 disposed troughs at equal intervals throughout its length, and having also rectangular apertures between said transverse troughs.

7. In mold construction, the combination of two complementary molds disposed adjacent and parallel to one another, said molds being formed to provide a horizontal engaging face, when in such position, and a supporting member adapted to removably engage such horizontal engaging face on 80 said two molds.

Signed by me this 1st day of February 1912.

JOSEPH W. HOLMAN.
